UNITED STATES PATENT OFFICE.

HOWARD T. HALLOWELL, OF PHILADELPHIA, PENNSYLVANIA.

DESIGN FOR A SHAFT-HANGER.

SPECIFICATION forming part of Design No. 34,350, dated April 9, 1901.

Application filed March 7, 1901. Serial No. 50,271. Term of patent 14 years.

To all whom it may concern:

Be it known that I, HOWARD T. HALLOWELL, a citizen of the United States, residing in the city and county of Philadelphia, State of Pennsylvania, have invented and produced a new and original Design for Shaft-Hangers, of which the following is a specification, reference being had to the accompanying drawings, forming part thereof.

10 The leading feature of my design for a hanger is a frame composed of legs converging downwardly, each of said legs being composed of sides converging also downwardly, said legs having a clamp on their lower portions, a brace common to their intermediate 15 portions, and a plate securing the feet of said legs rigidly in position.

Figure 1 represents a side elevation of a hanger embodying my design. Fig. 2 represents an end elevation of Fig. 1.

In the drawings, A designates the hanger, having the legs B, which converge downwardly, said legs being composed of the sides C, which also converge downwardly.

D designates a brace common to the legs, 25 the lower portion of the latter having secured thereto the clamp E and the feet of said legs secured to the plate F.

Having thus described my invention, what I claim as new, and desire to secure by Letters 30 Patent, is—

The design for a shaft-hanger substantially as shown and described.

HOWARD T. HALLOWELL.
